UNITED STATES PATENT OFFICE

160,574

HACK SAW

Joel H. Carlson, Chicago, Ill.

Application August 13, 1947, Serial No. 140,845

Term of patent 3½ years

(Cl. D93—4)

To all whom it may concern:

Be it known that I, Joel H. Carlson, a citizen of the United States, residing at Chicago, in the county of Cook and State of Illinois, have invented a new, original, and ornamental Design for a Hack Saw, of which the following is a specification, reference being had to the accompanying drawing, forming part thereof.

Fig. 1 is a front elevational view of a hack saw, showing my new design.

Fig. 2 is a top plan view, and

Fig. 3 is a bottom plan view.

I claim:

The ornamental design for a hack saw, as shown.

JOEL H. CARLSON.
